UNITED STATES PATENT OFFICE.

JOSEPH ALEXANDER PRICE, OF NEW YORK, N. Y.

DEVICE FOR ATTACHING AND DETACHING ELECTRIC BULBS.

1,210,835.

Specification of Letters Patent. Patented Jan. 2, 1917.

Application filed June 18, 1915. Serial No. 34,880.

To all whom it may concern:

Be it known that I, JOSEPH ALEXANDER PRICE, a citizen of Scotland, residing at New York, in the county of New York and State 5 of New York, have invented certain new and useful Improvements in Devices for Attaching and Detaching Electric Bulbs, of which the following is a specification.

This invention relates to devices for attaching and detaching electric bulbs, especially where the bulbs cannot be conveniently reached from the floor.

An object of the invention is to provide a device which is equally adaptable for use 10 with bulbs depending from the ceiling, etc., or projecting laterally from the wall.

Another object resides in the provision of mechanically expandable and contractible bulb engaging members, the latter being 15 likewise inherently expandable and contractible, to accommodate various sizes of bulbs therein, through the medium of the same component parts.

Other objects as well as the nature, character 20 and scope of my invention will be more readily understood from the following description taken in connection with the accompanying drawings and pointed out in the claims forming a part of 25 this specification.

Referring to the drawings, Figure 1 is a side elevational view of the device constructed in accordance with my invention and illustrating its application, Fig. 2 is a 30 fragmentary sectional view of the device, showing to advantage the interior of the housing and the details associated therewith, Fig. 3 is a horizontal sectional view through the housing of my improved device, a portion thereof being shown in fragmentary section to disclose details, this view likewise illustrating the application of the invention, Fig. 4 is a detail enlarged fragmentary sectional view of the device illustrating to advantage the manner in which the bulb engaging member is mechanically contracted, Fig. 5 is a detail enlarged fragmentary sectional view of the standard and handles used in the present invention, illustrating to advantage the manner of association of the same, Fig. 6 is a sectional view taken on the line 6—6 of Fig. 1, Fig. 7 is a detail enlarged perspective view of the rotatable cap with which the bulb embracing member is engaged, and Fig. 8 is a detail enlarged perspective fragmentary view of the housing.

The device embodies a tubular standard 1, the upper end of which supports a housing 2, the latter being of a rectangular configuration and having one side thereof removable, whereby access may be had to the interior of the housing. A stud 3 is arranged on the top of the housing 2, and is adapted for engagement with the bulb embracing member hereinafter described. A pin 4 extends transversely through the stud 3 and appreciably beyond the outer periphery of the latter at diametrically opposite points.

A shaft 5 is rotatably mounted in the tubular standard 1, the lower end of which is reduced and screw-threaded as indicated at 6 and shown to advantage in Fig. 5, for screw-threaded engagement in a handle 7, the latter being of any desired configuration, so as to be conveniently grasped by the hand of the user of the device, to permit rotation of the shaft 5 with which the handle is associated. It will be noted that the inner terminal of the handle 7 is provided with an annular depressed portion 8, which receives the lower end of the tubular standard 1. The upper end of said shaft 5 has a beveled gear 9 fixedly engaged therewith, the gear 9 coming into mesh with a beveled pinion 10, in order to impart movement to the latter, when the shaft 5 is rotated. As illustrated to advantage in Fig. 2, the gear 9 is engaged with the lower end of the housing, while the gear 10 is engaged with one side thereof, said latter gear being provided with a threaded bore which is engaged in screw-threaded relation with the threaded shank 11 of a tubular shaft 12. The threaded end 11 of the shaft 12 extends laterally beyond one side of the housing and is in threaded engagement with a nut 13, the latter having pintles 14 extending from its periphery for a purpose hereinafter set forth. The other end of the shaft 12 is extended through an opening in the opposite wall of the housing with which the gear 10 is engaged, and has threaded thereon a nut 16, the latter providing a bearing for the shaft 12 and being loosely mounted through an opening in the housing. As illustrated to advantage in Fig. 2, the gear 10 is threaded on the shaft 12 as far as possible, after which the nut is rotated into intimate contact with said gear, so as to prevent movement of the latter independently of the shaft 12.

The bulb embracing member is generally designated in the drawings at 17 and con-

sists of a cap 18, preferably of a cylindrical configuration, one end of which is in abutting engagement with one side of the housing 2, as illustrated to advantage in Figs. 3 and 4. The end of the cap 18 which abuts the housing 2 is open, while the opposite end is closed and has mounted thereon a threaded shank 19, in which is mounted a plurality of fingers 20, each of which comprises a strand of wire, the free ends of which are embedded in the shank 19, each strand of wire being depressed approximately midway its ends after having been engaged with the shank 19, so as to provide a substantially ovoid structure, when the fingers are all in assembled relation, as illustrated to advantage in Figs. 1 and 3. The outer terminals of the fingers 20 are flared outwardly so as to facilitate engagement with an electric bulb, the latter being indicated in the drawings at 21. It is of course, understood that the fingers 20 are of an inherently resilient nature, so as to be adaptable for use with electric bulbs of various sizes. It is well known, however, that with inherently resilient members the same are very readily distorted by constant use, so as to be rendered unsuitable for use, after a comparatively short length of time for use in connection with smaller objects, and for this reason a mechanical means is provided for contracting the fingers 20, and permitting the latter to be automatically expanded upon retraction of the mechanical means. The mechanical means in the present instance embodies a sleeve 22, having an internally screw-threaded portion for threaded engagement with the shank 19, and movable on the latter for contracting the fingers 20, as illustrated to advantage in Fig. 4. It will be noted that the bore on the outer end of the sleeve 22 is flared so as to facilitate contraction of the fingers 20, when pressure is exerted on the sleeve 22, for operating the latter into engagement with the fingers. In use, therefore assuming that it is desired to use the device in connection with laterally projecting electric bulbs, the bulb embracing member 17 is slidably engaged with the nut 13, and in order to prevent the displacement of the member from said nut, a bayonet groove 23 has been formed in the cap 18 of said embracing member, which is adapted to receive the members 14

therein. After this operation, pressure is exerted on the handle end 7 of the device, so as to rotate the shaft 5, consequently imparting movement to the meshing gears 9 and 10 for communicating movement to the bulb embracing member in order to rotate the bulb in the desired direction. If desired to remove bulbs depending from a ceiling, etc., the bulb embracing member 17 is engaged with the stud 3, and the member 4 of said stud engaged in the bayonet grooves 23 of the cap 18, in order to prevent casual displacement of the latter. In this instance, the entire device is bodily movable, thereby rotating the bulb embracing member, which is superimposed on the housing 2, for rotating said bulb embracing member, in the direction of movement of the device.

It will be understood that the above description and accompanying drawings comprehend only the general and preferred embodiment of my invention and that various minor changes in details of construction, proportion and arrangement of parts may be made within the scope of the appended claims without sacrificing any of the advantages of my invention.

Having thus fully described my invention, what I claim as new and desire to secure by Letters Patent is:

1. A device for attaching and detaching electric bulbs including a bulb embracing member, means in connection with said member for rotating the latter, a housing for completely inclosing said means, and secondary means for imparting movement to the aforementioned means.

2. A device for attaching and detaching electric bulbs including a polygonal housing, a bulb embracing member in connection with one face of the housing and movable independently of the latter for use in connection with laterally extending bulbs, and means mounted on another face of the housing to receive said member, the latter adapted to move as an entirety with the housing for use with vertically depending bulbs.

In testimony whereof I affix my signature in presence of two witnesses.

JOSEPH ALEXANDER PRICE.
